CLAIM

I claim the ornamental design for a tool grip, as shown and described.

DESCRIPTION

FIG. 1 is a perspective view for a tool grip showing my new design;

FIG. 2 is a side view thereof;

FIG. 3 is a front view thereof;

FIG. 4 is a bottom view thereof;

FIG. 5 is a top view thereof; and,

FIG. 6 is a rear view thereof.

The broken lines represent portions of the tool grip that form no part of the claimed design.
